UNITED STATES PATENT OFFICE

121,432

DESIGN FOR A COAT OR SIMILAR ARTICLE

Sol Vogel, Brooklyn, N. Y.

Application February 26, 1940, Serial No. 90,506

Term of patent 3½ years

To all whom it may concern:

Be it known that I, Sol Vogel, a citizen of the United States, residing in the Borough of Brooklyn, city of New York, county of Kings, and State of New York, have invented a new, original, and ornamental Design for a Coat or Similar Article, of which the following is a specification, reference being had to the accompanying drawing, forming part thereof.

The characteristic feature of my design resides in the specific combination on the coat disclosed in the front yoke portion, which yoke extends over the shoulder into the back, as shown.

I claim:

The ornamental design for a coat or similar article, as shown and described.

SOL VOGEL.
